GRAIN CLEANING MACHINE

Alfred Schär, Wallisellen, Switzerland

Application September 10, 1948, Serial No. 48,719
In Switzerland September 12, 1947

3 Claims. (Cl. 209—481)

1

This invention concerns a machine for cleaning grain, particularly for separating specifically heavy foreign bodies, for example stones from cereal grains, such as wheat or rice.

It is an object of the invention to separate stones or other relatively heavy bodies from grains, without the usual treatment of the grains in water, but solely by subjecting the grain to vibration in successive stages and to an air current.

To the accomplishment of this object and other objects as may hereinafter appear, my invention is directed to the machine for cleaning grain as described in the following specification and defined in the appended claims, taken together with the annexed drawings in which:

Fig. 1 is a side elevation of a machine according to the invention, comprising a stationary base casing and vibratory upper casing.

Fig. 2 is a horizontal section on line II—II of Fig. 3.

Fig. 3 is a vertical section on line III—III of Fig. 5.

Fig. 4 is an end view of the machine.

Fig. 5 is a vertical section on the line V—V of Fig. 3.

Fig. 6 is a horizontal section through the vibratory casing on the line VI—VI of Fig. 3.

Fig. 7 is a transverse section on the line VII—VII of Fig. 6.

Fig. 8 is a sectional detail view on the line VIII—VIII of Fig. 6.

Fig. 9 is a sectional detail view on the line IX—IX of Fig. 6.

Figs. 10 and 11 are sectional detail views on the lines X—X and XI—XI, respectively, of Fig. 6.

Fig. 12 is a vertical sectional detail view of an air current separating device, on the line XII—XII of Fig. 13.

Fig. 13 is a vertical section on line XIII—XIII of Fig. 12.

Fig. 14 is a horizontal section along the line XIV—XIV of Fig. 12.

Fig. 15 is a sectional detail view of a vibrating cone bottom receptacle.

The represented grain cleaning machine comprises an upper vibrating casing 1 and a lower stationary base casing 2. In the upper casing 1 are mounted in series three pairs of vibrating troughs 3 and 4, 5 and 6, and 7 and 8. These troughs are inclined in longitudinal direction, that is in the direction of flow of the material to be cleaned, as shown in Fig. 3, while in transverse direction, as shown in Fig. 7, the bottom of the trough is inclined from both longitudinal sides towards the center, where each trough is provided with a longitudinal channel 9, extending the whole length of the trough. At the discharge end of the trough 3 a fixed tongue 10 is disposed

above the channel 9 and secured to the frame of the vibratory casing 1. The tongue 10 is spaced from the bottom of the channel and its purpose is to divide the stream of grains flowing down the channel in two streams, a portion of the grains passing below the tongue and another portion above the tongue. A similar tongue 11 is placed above the end of the channel 9 in the trough 4; tongues 12 and 13 are disposed in similar manner at the discharge ends of the channels in the troughs 5 and 6, and further similar tongues 14 and 15 are provided above the outlet ends of the central channels 9 in the troughs 7 and 8. The end of the channels 9 in the troughs 3 and 4 discharge into a vertical conduit 16 (Figs. 3, 5 and 8), the channels 9 of the troughs 5 and 6 discharge into a vertical conduit 17 (Figs. 3 and 10), and the channels 9 of the troughs 7 and 8 discharge into a vertical conduit 18.

Two superposed receptacles 19 and 20 are supported by the vibratory casing 1 below the vertical conduit 16 to receive the material falling down through this conduit. These receptacles (Fig. 15) are provided with a cone-shaped bottom 21, having its highest point or summit located in the center of the receptacle and perforated at 23. The bottom 21 is surrounded by an upstanding rim 22. Below the outlet of the vertical conduit 18 are disposed two groups of similar superposed receptacles 24, 25, 26 and 27, and 28, 29, 30, 31 and 32, each of these receptacles being provided with a cone-shaped bottom having a hole 23 at the summit. The holes of the various receptacles gradually decrease in diameter from the highest receptacles of each group to the lowermost receptacles. A floor 33 (Figs. 3 and 6) forming part of the vibratory casing 1 collects material which falls over the rim 22 of the cone bottom receptacles 19 and 20, and 24 to 32, and delivers it to an outlet 34. The inlet of the grain to be cleaned into the vibratory casing 1 is designated by 35.

The vibrating casing 1 is carried by four groups 40, 41, 42 and 43 of three elastic rods each; these rods are vertically disposed and are secured by their upper ends in brackets 44 and 45 on the upper outside walls of the casing 1, while their lower ends are carried in brackets 46 and 47 of the base casing 2. The vibratory casing 1 is accordingly resiliently movable. The casing 1 carries a journal bearing 39 for guiding a crank pin 52 of a rotary shaft 50. This shaft is rotatably mounted in a bearing 48 carried by a transverse beam 49 of the base casing 2, and is provided with a radial arm 38 carrying a compensating weight 51. A driving pulley 53 is mounted on the bottom end of the shaft 50.

A driving shaft 54 is mounted in bearings 56 outside of the casing 2. One end of the shaft carries an eccentric pin 55 journalled in the head

37 of a connecting rod 57 (Figs. 1 and 2). The rod 57 is pivotally connected to an arm 58 which is secured to a pipe section 59 forming part of a blow pipe. The outlet of this pipe forms three nozzles 60, 61 and 62 (Fig. 12) ending each in a channeled tongue 63, 64 and 65, respectively. The inner end of the pipe section 59 is connected by means of blade springs 66 to the blow pipe section 67 connected to the delivery end of a blower 68. When the shaft 54 rotates, the eccentric pin 55 imparts a to-and-fro movement to the connecting rod 57 which, by the intermediary of the arm 58 produces a vibratory motion of the pipe section 59 with the nozzles 60, 61, 62, and the channeled tongues 63, 64 and 65.

The blower 68 is provided with a central air inlet 69 (Figs. 3 and 4) and the amount of aspirated air is controlled by means of a throttle disc 70 connected by links 71 to a hand lever 72 on the outside wall of the casing 2, by means of which lever the throttle disc 70 can be raised or lowered to open more or less the air inlet 69 and accordingly to create a more or less intensive air stream through the delivery conduit 67, 59. The air delivered by the nozzles 60, 61 and 62 is exhausted from the casing 2 through the outlet 75.

The driving shaft 54 carries a pulley 73 which drives by means of a belt 74 the pulley 53 of the shaft 50 of the vibratory casing 1. The shaft 54 may be driven by a not represented motor which will be connected by a belt drive to the pulley 74 on the shaft 54.

The vibrating troughs 3, 4, 5, 6, 7 and 8 are preferably made of pressed sheet metal and are provided with straight ribs 76 projecting above the bottom of the troughs (Figs. 6 and 7). These ribs extend from both longitudinal sides of the troughs in oblique direction relative to the flow of the material in the trough, into the central channel 9.

The described grain cleaning machine operates in the following manner: The material to be cleaned, from which stones and other relatively heavy bodies are to be removed is continuously fed through the inlet 35 to the two troughs 3 and 4. The driving shaft 54 is in operation and by means of the belt 74 the shaft 50 is caused to rapidly rotate, so that the eccentric pin 52 imparts an oscillating vibratory motion to the casing 1 and to the entire structure of troughs and receptacles supported thereby. The material on the troughs 3 and 4 slides slowly downwards, the relatively heavy stones falling to the bottom of the troughs where they are directed towards the central channel 9 by the ribs 76. At the discharge end of the troughs 3 and 4, the lowermost layer of material in the channels 9, which layer comprises most of the stones, flows underneath the tongues 10 and 11, respectively, into the conduit 16 according to the arrows 77 (Figs. 3 and 8) and falls into the cone bottom receptacles 19 and 20.

The layer of material flowing over the tongues 10 and 11, and the material discharged from the troughs 3 and 4 laterally of the central channel 9 falls through open spaces 78 and 79 between the end of the trough bottoms and the partition 80 (Figs. 3, 6 and 9) on the next following pair of troughs 5 and 6. These troughs are identical with the troughs 3 and 4. The stones which are still left in the material tend again to flow towards the central channels 9 of these two troughs. At the discharge ends of these troughs the lowermost layer of material in the channels 9, contain-

ing again most of the stones remaining in the material, flows underneath the tongues 12 and 13 into the conduit 17 and down an inclined chute 81 (Figs. 3 and 10) which delivers the stone containing material to the upper cone bottom receptacles 28, 29 and 30, and 24, 25 of the two groups of receptacles. The material of the troughs 5 and 6 flowing over the tongues 12 and 13 and the material discharged from these troughs laterally of the central channels 9 falls through open spaces 82 and 83 between the end of the bottoms of these troughs and the partition wall 84 (Figs. 3, 6 and 11) into the next following pair of troughs 7 and 8. The same stone separating action is repeated in these two troughs. The lowermost layer of material in the central channels 9 of the troughs 7 and 8, which layer may still contain stones, flows underneath the tongues 14 and 15 and is discharged into the upper cone bottom receptacles 24 and 23 of the two groups of receptacles. The trough bottom laterally of the central channels at the discharge end of the troughs 7 and 8 extends to the partition wall 80 (Fig. 3). The material on these bottom portions, after having successively passed through three separating troughs is now free of stones and is discharged immediately through slots, not represented, in the partition wall 80, so as to fall on the floor 33 and arrive at the outlet 34.

The material delivered from the troughs 3 and 4 through the conduit 16 to the receptacles 19 and 20 is subjected to a further separation in the receptacles. As shown in Fig. 15, these receptacles have a conical bottom 21. The cone angle α may vary between 4° and 33° as has been determined by experience. The receptacles also are subjected to the circular vibratory movement imparted by the shaft 50 to the casing 1. When stone containing grain arrives on the vibrating receptacles it can be observed that the specifically heavier stones tend to rise on the conical surface towards the center thereof, while the specifically lighter kernels remain near the periphery of the cone-shaped bottom. Accordingly the stones slowly move towards the summit of the cone when the receptacle 19 vibrates and eventually fall through the central hole 23 of the bottom, while the kernels fall over the rim 22 of the receptacle, either into the lower receptacle 20 or through the opening 84 in the wall 80. Naturally, a portion of the kernels also will fall through the central holes 23 of both receptacles 19 and 20, but no stones will fall over the periphery of the receptacles. In the lower receptacle 20 the same separation is repeated, the stones and a portion of the kernels fall through the central hole of the cone-shaped bottom while kernels only are discharged through the opening 85 in the wall 80 and arrive on the floor 33 on which they pass to the outlet 34.

The stones and kernels which pass through the central holes 23 of the receptacles 19 and 20 fall through the conduit 18 and arrive in the two upper receptacles 24 and 28 of the two adjacent groups of cone bottom receptacles. In the superposed receptacles the separation of stones is further carried out in the same manner as in the receptacles 19 and 20 just described. Stones and a certain amount of kernels fall through the central holes 23, while kernels without any stones are discharged over the peripheral rims of the various receptacles into the next lower receptacle or through openings 86 in the wall 80 and fall on the floor 33 to pass to the outlet 34.

The material which traversed the central holes

of the superposed cone bottom receptacles, which comprises a large percentage of stones, falls on an inclined wall 37 which delivers it to an inclined tongue 38 (Figs. 3, 5 and 12) above the blower nozzles 60, 61 and 62. From this tongue 38 the material falls down on the channeled tongue 63 in front of the nozzle 60, the nozzle and tongue 63 effecting a vibratory movement which is imparted to the pipe section 59 by the eccentric pin 55 of the drive shaft 54. As soon as the material, falling off the tongue 38 arrives in the air current of the nozzle 60, the lighter kernels are blown in the direction of the arrow 89 into the outlet collector housing 90, from which they fall down on the inclined chute 91 and into the outlet pipe 92 disposed underneath the outlet 34 for the grain which has been collected by the floor 33. Owing to the triangular section of the channels of the tongue 63, the intensity of the air current is smaller near the narrow bottom of the channels, due to friction along the walls of the channel, than at the wider top of the channels. The heavier stones fall to the bottom of the channels and are slowly ejected therefrom by the less intense air current. Since not all the kernels may have been blown off from the first tongue 63, the separating action is repeated. The stones and such kernels which have not been blown into the housing 90 fall from the channeled tongue 63 to a collecting sheet 93 which is also carried by the blow pipe section 59 and accordingly subjected to vibrations. This collecting sheet delivers the material in front of the second air nozzle 61 on the channeled tongue 64. The lighter kernels are again blown away into the housing 90 and fall into the chute 91 and outlet 92, while the heavier stones fall into the channels of the tongue 64 and are blown slowly out of the channels to fall on a further collecting sheet 94 which again delivers the collected material to the third channeled tongue 65 in front of the nozzle 62. A final separation of stones and kernels takes place, the kernels are blown into the housing 90 and the stones fall on the inclined surface 95 and from there into the stone outlet 96.

The grain collected below the outlet pipe 92 is practically free of stones. If material is treated which contains a relatively high percentage of stones or other heavy foreign particles, it is possible to direct the material from the outlet 92 on an elevator device which brings it again to the inlet 35 of the vibrating casing 1, so as to cause the material to repeatedly flow through the machine until all stones have been completely removed.

It will be understood that while I have shown and described one method of carrying my invention into effect, various changes and modifications of the construction herein shown and described may be made, particularly the number and disposition of the various vibrating troughs and receptacles may be altered, within the scope of the appended claims and without departing from the spirit of my invention.

I claim:

1. In a grain cleaning machine, a stationary lower casing, a movable upper casing carried by substantially vertically disposed elastic rods supported by their lower ends in said lower stationary casing, said lower casing supporting a substantially vertical rotatable shaft provided with an eccentric extension engaging said movable upper casing, whereby upon rotation of said shaft a substantially circular horizontal vibratory motion is imparted to the upper casing, a series of super-

posed receptacles carried by said upper casing for vibratory movement therewith, means in said upper casing for directing a stream of granular material to be cleaned to said receptacles, each receptacle having a cone-shaped bottom provided with a perforation at the central peak of the bottom and with an upstanding rim surrounding the peripheral edge of the bottom, the bottom surface sloping downwards in all directions from said central perforated peak towards the peripheral rim of the bottom, whereby upon vibratory movement of said receptacles the specifically heavy particles will rise towards the peak of the cone-shaped bottom and discharge through said perforation, while the specifically lighter grains will discharge over said peripheral rim of the bottom.

2. In a grain cleaning machine, a stationary base, a movable casing suspended in said base, said casing being carried by substantially vertically disposed elastic rods supported by their lower ends in said base, means mounted in said base to impart a circular vibratory movement to said movable casing, said means including a substantially vertical rotatable shaft having an eccentric extension engaging said movable casing, a series of superposed receptacles carried by said movable casing for circular vibratory movement therewith, means in said upper casing for directing a stream of granular material to be cleaned to said receptacles, each receptacle having a cone-shaped bottom provided with a perforation at the central peak of the bottom and with an upstanding rim surrounding the peripheral edge of the bottom, the bottom surface sloping downwards in all directions from said central perforated peak towards the peripheral rim of the bottom, whereby upon rotation of said shaft and vibratory movement of said receptacles the specifically heavy grains will rise towards the peak of the cone-shaped bottom and discharge through said perforation, while the specifically lighter grains will discharge over said peripheral rim of the bottom.

3. A grain cleaning machine as defined in claim 1, wherein the perforations at the central peak of the conical bottoms of a series of superposed receptacles gradually decrease in diameter from the highest receptacle to the lowermost receptacle of said series.

ALFRED SCHÄR.
